BOBBIN WINDING MACHINE

Ernst Schweizer, Zurich, Switzerland

Application February 7, 1930, Serial No. 426,657
In Germany February 8, 1929

6 Claims. (Cl. 242—18)

This invention relates to bobbin winding machines and more especially to machines which are used for winding a thread of artificial silk upon a bobbin. In addition to this, my invention relates to a novel method of operating bobbin winding machines and of winding thread upon a bobbin.

My invention may be used with advantage for winding cylindrical as well as conical bobbins which, moreover, may be bevelled at one or both of their ends. My invention furthermore provides a novel machine for making cross-wound bobbins as well as a novel method of winding bobbins of this kind.

15 A primary object of my invention, as far as it relates to the method of winding bobbins, especially bobbins of artificial silk, consists in providing possibilities to wind the bobbins at even speed of the thread, independently of their temporary 20 thickness which increases during winding, and to dispense at the same time with any roller which had ordinarily been used for driving the bobbin.

A further object of my invention consists in a 25 novel construction of a cross-winding machine for making cylindrical bobbins.

A still further object of my invention consists in a novel construction of a cross-winding machine which may be used for winding bobbins which are bevelled on one or both of their ends.

30 A still further object of my invention consists in a novel construction of a cross-winding machine for winding conical bobbins in which, in addition to the conical shape, one or both ends of the bobbins may be bevelled. For this special 35 purpose I make use of a change speed drive permitting to maintain automatically the speed of the thread at a constant value, while the thickness of the bobbin increases during the process of winding. The thread-guide of the present 40 machine, is connected with a feeding device permitting to vary and adjust automatically the path of motion of said thread-guide. This feeding device in conjunction with a swingable bail will permit adjustment of the driving mechanism 45 of the thread-guide with respect to the cam disk in radial direction to the latter's axis of rotation and impart a swinging motion to said thread-guide relatively to the cam disk. This swinging motion now is transmitted, for instance, to a friction 50 drive in such a manner that the driving disk of said friction drive is displaced with respect to the driven disk in radial direction towards the periphery of the latter, this effecting a gradual reduction of the speed of rotation of the spindle 55 which serves for rotating the bobbin, thus dis-

pensing with the roller for the immediate drive of said bobbin. In this manner a uniform speed of the thread to be wound upon the bobbin will be the result in spite of the increase of the diameter of the latter during the process of winding. 60 In other words, the speed at which the thread is wound upon the bobbin will have a constant value, say, 250 meters per minute, and during the process of winding no injurious strains whatever will be imposed upon the thread, even in case the latter 65 is wound at a high speed upon the bobbin. This is of great importance, especially when winding threads of artificial silk upon a bobbin.

My new winding machine may also be used in connection with conical bobbins, the cam disk 70 which rotates obliquely around its axle being in this case controlled by means of a further gearing comprising elliptical gear wheels, the retardation and acceleration produced thereby being positively transmitted to the guide-thread with the result 75 that, in spite of the conical form of the bobbins, the speed at which the thread is wound upon the latter is kept continuously uniform and independent of the thickness of the bobbin.

The bobbin winding machine may be constructed 80 according to my invention either for winding one bobbin at a time or also for winding a plurality of bobbins simultaneously.

In the accompanying drawings I have represented two preferred forms of construction of my 85 new machine which serves for the cross-winding of bobbins, Fig. 1 being a longitudinal section, with several parts in view, of a machine serving for the purpose of uniform cross-winding of cylindrical bobbins which may be bevelled either at 90 one or both of their ends, Fig. 2 a top-view taken on Fig. 1, several parts being shown in section, Fig. 3 a section on the line A—B of Figure 1 of my new bobbin winding machine as seen in direction from the feeding device, showing in particular the swinging motion of the thread-guide 95 which motion is controlled by said feeding device, Fig. 4 an enlarged detail-view of said feeding device, Fig. 5 a plan-view, partly in section, of a machine for making cross-wound conical bobbins which may likewise be bevelled either at one 100 or both of their ends, and Fig. 6 a section along line C—D of Fig. 5 showing in particular the elliptical wheel gearing which serves for driving the bobbin at varying angular velocity.

Referring now more particularly to the drawings—in which like parts are designated with like reference numerals—the driving shaft 1 which is operated by motor power is provided with a key-way 2, a disk 3 forming part of a friction drive 110

being mounted displaceably in axial direction upon said shaft 1 by means of a key co-operating with said keyway 2. The friction disk 3 is provided with a guide cylinder 4 having an angular groove 5, a roller 6 mounted at the end of a swinging lever 7 engaging with said groove 5. The friction disk 3 is in frictional engagement with the driving disk 8 which latter is fixedly connected with the axially displaceable shaft 9. A spring 10 serves for pressing said shaft 9 against the friction disk 3, said spring 10 being releasable by means of the lever 11. The shaft 9 carries a gear-wheel 12 which is in mesh on the one hand with a gear-wheel 13 on the main shaft 16 and on the other hand with a gear-wheel 14 on the spindle 15. The latter carries the reel or bobbincylinder upon which the thread of artificial silk is wound to subsequently form the bobbin. The gear-wheel 13 is in mesh with a gear-wheel 14' on the shaft 15', the latter serving to drive a second bobbin. The shaft 16 carries a cam disk 17 and forms the axis of rotation for said cam disk. The guide-member 18 forms part of the thread-guide and engages with the periphery of said cam disk 17 in such a manner that said guide-member 18, during rotation of the shaft 16, will be positively reciprocated in a direction parallel to the shaft 16, that is to the axis of rotation of the cam disk. The guide-member 18 is mounted slidably upon the hollow shaft 21 as well as upon a guide-rod 19 which latter is rigidly mounted on both of its ends within connecting members 20 fast on said hollow shaft 21. A guide-rod for the thread is slidably mounted within the hollow shaft 21, the latter being provided with a longitudinal slot and a screw passing therethrough and being connected with the member 18 of the thread-guide. The connecting members 20 are mounted rotatably in the wall of the casing 24 and connected rigidly with the swinging lever 7. Intermediate the wall 24 of the casing and the connecting members 20 there are provided two torsional springs 25 tending to keep the guide-members 18 in engagement with the periphery of the cam disk 17. One of the members 20 is connected by way of a flexible wire 26 with a feeding device which is actuated from the main shaft 16. The latter projects out of the casing 24 and carries at its projecting end a disk 27 which is equipped with a groove 28. A crank-pin 29 is fixed on said disk 27 radially adjustable thereto and engages with said groove 28. The crank-pin 29 actuates the lever 30 swingably mounted upon the shaft 31 and carrying a pawl 32. A feed-wheel 33 is mounted upon the shaft 31, said feed-wheel being in rigid connection with a worm 34 which transmits motion to the worm-wheel 38. The latter is mounted upon a shaft 36 which drives the worm-wheel 38 by means of the worm 37. The worm-wheel 38 is mounted upon the shaft 39 which is provided with a handle and an eccentric 40 fast on said shaft. The worms 35 and 37 as well as the shaft 36 are mounted within a bail 41 which is firmly connected with the casing 24. A wire 26 leading to the connecting member 20 is fastened to the periphery of the eccentric 40. The cam or eccentric 40 may be made exchangeable, if desired.

A bail 42 which is bent off at its free end is fixed to the connecting member 20, the wire 26 being carried over said free end of said bail. The bent off free end of the bail 42 as well as the eccentric 40 are of such conformation that the rotation of the hollow shaft 21 and therewith the adjustment of the friction wheel 3 will be adjust-

ably dependent upon the speed of rotation of the shaft 16.

Cross-wound bobbins may be made at a constant speed of the thread during increasing diameter of the bobbin in the following manner.

The friction disk 3 which is mounted displaceably upon the motor-driven shaft 1 is adjusted at the start of the process of winding to be positioned at the center of the driven disk 8. The spindles 15 and 15' upon which the bobbins are wound will thus be given the greatest speed of rotation so that, for instance, 250 meters of thread per minute may be wound upon the empty bobbincylinder. The cam disk 17, when rotating, will reciprocate the member 18 which forms part of the thread-guide. The disk 27 on the shaft 16 now actuates intermittently the feed-wheel 31 by means of the lever 30. Rotation of the feed-wheel is transmitted by means of the worm 34 to the worm-wheel 35, and further to the worm-wheel 38 by way of the worm 37. The worm-wheel 38 mounted upon the axially displaceable shaft 39 drives the eccentric 40, thus adjusting by means of the tension wire the bail 42 and therewith also the rod mechanism 18, 19, 21 against the action of the spring 25. This motion now serves to adjust the guide-member 18 with respect to the cam disk 17. More particularly, this adjustment is effected towards the center of said disk as shown in dotted line in Fig. 3.

The swinging motion of the guide-member 18 around the shaft 31 is transmitted by means of the swinging lever 7 to the friction disk 3 which will thus be axially displaced and adjusted upon the driving disk 8 in a direction towards the periphery thereof. The amount of rotation of the spindles 15 and 15' will now be gradually decreased in accordance with the increasing diameter of the bobbins and the speed at which the thread is wound upon the bobbin will thus be kept uniform, irrespective of the increase of the diameter of the bobbin.

In order to permit threads of widely different diameters to be wound upon the bobbins at even speed of winding, the degree of intermittent feeding is varied on the feeding device by radially adjusting the crank-pin 29 on the disk 27, as may be seen from Fig. 4.

After completion of a bobbin the shaft 39 is adjusted until the wheel 38 comes out of engagement with the wheel 37. By rotating the shaft 39 into the position shown in dotted lines in Fig. 3 the disk 14, and therewith the members 18, 19 and 21, as well as the friction disk 3 will be moved back into their initial position. The wheel 38 is now again caused to come in engagement with the wheel 37 so that the machine will be ready for winding another bobbin.

The machine which according to my invention may be used for making cross-wound conical bobbins having a bevel either at one or both of their ends, as indicated in Figs. 5 and 6, is constructed principally in accordance with the aforescribed machine, as far as the friction drive 1, 2, 3, 4 and 8 for the shaft 16 and the wobbling disk 17 actuating the thread-guide 18—20, 25 and the feeding device 26—30, 32, 33, 38—41 are concerned. In the present case the drive, however, differs from the drive of the aforescribed machine, in that an elliptical gear-wheel drive is provided instead of the train of plain gear-wheels 12—14'. Mounted upon the spindle of the friction wheel 3 is a gear-wheel 42 which is in mesh with a gear-wheel 43. A further gear-wheel 44 is mounted upon the shaft of the gear-wheel 43, said gear-

wheel 44 meshing with the gear-wheel 45. This shaft—which according to the drawing is positioned in the rear—carries in addition to the gear-wheel 45, for instance, an elliptical gear-wheel 47 which is in mesh with an elliptical companion gear-wheel 48 fixed on the main shaft 16.

Upon the main shaft 16 there is also mounted the gear-wheel 49 which meshes with the gear-wheel 54. The latter is mounted upon the driving shaft 15 for the bobbin. Upon the shaft 16 there is further mounted the cam disk 17 which reciprocates the members 18, 18' of the thread-guide upon the shaft 19, 21. The thread directing member 53 guides the threads (not shown) to reciprocate along the bobbin 50 which may, for instance, be of conical conformation and thus the bobbin will be wound crosswise. In order to wind the thread in like manner onto the bobbin 50 on both points 51 and 52 thereof, the bobbin 50 is rotated in the latter case at about triple speed, the increase of speed being effected by means of the elliptical gear-wheels 47 and 48.

I claim:

1. A cross spool machine for the production of cylindrical or conical spools with beveled ends, including a power shaft, a frictional gear drive operated by the power shaft, a main shaft driven by the frictional gear drive, a cam disk on the shaft, a guide shaft arranged parallel to the main shaft, a thread guide slidable on the guide shaft, said guide cooperating with the cam disk to compel sliding movement of the guide with the operation of the cam disk, a second guide shaft mounted parallel to the first guide shaft and capable of a movement of revolution with respect to the first guide shaft, said thread guide being slidably mounted on said second guide shaft, a lever controlled by the movement of revolution of the second guide shaft for governing the friction gear drive to control the speed thereof, and means driven by the main shaft for controlling the position of the lever, said means including an eccentric, and a connection between the eccentric and the second guide shaft to impart revolving movement to the second guide shaft in the rotation of the eccentric and thereby operate the lever for controlling the speed of the friction gear drive and simultaneously swing the thread guide to vary its cooperation with the cam disk.

2. A cross spool machine for the production of cylindrical or conical spools with beveled ends, including a power shaft, a frictional gear drive operated by the power shaft, a main shaft driven by the frictional gear drive, a cam disk on the shaft, a guide shaft arranged parallel to the main shaft, a thread guide slidable on the guide shaft, said guide cooperating with the cam disk to compel sliding movement of the guide in the operation of the cam disk, a second guide shaft mounted parallel to the first guide shaft and capable of a movement of revolution with respect to the first guide shaft, said thread guide being slidably mounted on said second guide shaft, a lever controlled by the movement of revolution of the second guide shaft for governing the friction gear drive to control the speed thereof a grooved disk carried by the main shaft, a pawl lever operated by said disk, a worm given a step by step movement by the pawl lever, a worm gear operated by said worm, an eccentric driven by said worm gear, and a wire carried by the eccentric and connected to the second guide shaft to compel a movement of revolution of said shaft for operating the lever for controlling the

friction gear drive and for shifting the thread guide with respect to the cam disk.

3. A bobbin winding machine including a power shaft, a main shaft, a frictional gear drive between the power shaft and main shaft, a lever for shifting one of the frictional elements of said drive with respect to the other for varying the speed of the drive, a guide shaft arranged parallel to the main shaft, a thread guide slidable on the hollow shaft, a second guide shaft on which the thread guide is slidable, said second guide shaft being connected to and controlling said lever and mounted for revolution with respect to the first mentioned guide shaft, a cam disk secured on the main shaft and cooperating with the thread guide to compel traverse of the latter, and mechanism operated by the main shaft and including an eccentric connected to the second guide shaft for compelling revolution of the latter with respect to the first guide shaft for simultaneously moving the lever and shifting the thread guide with respect to the cam disk.

4. A bobbin winding machine including a main shaft, a power shaft, a friction drive between said shafts, a lever for shifting one element of the friction drive to thereby control the speed thereof, a thread guide mounted for sliding movement, a guide shaft on which the thread guide is mounted for sliding movement and with respect to which it is capable of rotation, a cam disk mounted on the main shaft, arms projecting from the thread guide and engaging said disk to compel traverse movement of the thread guide in the operation of the disk, means whereby rotative movement of the thread guide will operate said lever for controlling the speed of the friction drive, an eccentric, a connection between the eccentric and thread guide to compel rotative movement of the latter for shifting the lever and moving the arms of the thread guide with respect to the cam disk to adjust the length of the traverse of the thread guide, and means controlled by the main shaft for operating the eccentric.

5. A bobbin winding machine including a main shaft, a power shaft, a friction drive for transmitting power from the power shaft to the main shaft, a lever for shifting one of the elements of the friction drive to control the speed of the drive, a guide shaft arranged parallel to the main shaft, a thread guide slidable on the guide shaft, a second guide shaft mounted for swinging movement with respect to the first mentioned guide shaft, a sliding connection between the thread guide and the second guide shaft, a connection between the second guide shaft and lever whereby the swinging movement of the second guide shaft will operate the lever, a cam disk on the main shaft, arms carried by the thread guide and bearing on opposite sides of the cam disk, said cam disk compelling transverse movement of the thread guide in the operation of the main shaft, an eccentric, and means driven by the main shaft for imparting a step by step movement to the eccentric, and a wire connected to the eccentric and to the second guide shaft to compel swinging movement of the latter in the direction of the eccentric.

6. A bobbin winding machine including a power shaft, a main shaft, friction driving means between the power shaft and main shaft, a cam disk arranged at an angle to and mounted on the main shaft, a thread guide, a guide shaft on which the thread guide is slidably mounted, said thread guide having arms to engage the

cam disk to permit said cam disk to compel transverse movement of the thread guide in the operation of the main shaft, a second guide shaft on which the thread guide is slidably mounted, 5 sleeves mounted on the first guide shaft and having connecting members extending therefrom to support the second guide shaft, whereby the second guide shaft is bodily movable with respect to the first mentioned guide shaft, springs for 10 normally holding the guide shafts in normal relative positions, a step by step mechanism driven by the main shaft, an eccentric, gearing

intermediate said step by step mechanism and said eccentric, and a wire connected to the eccentric and to one of said connecting members to compel bodily movement of the second guide shaft with respect to the first mentioned guide shaft, whereby to move the lever for controlling the speed of the friction drive and shifting the arms with respect to the cam disk to vary the length of traverse of the thread guide in the 80 operation of the main shaft.
